FIRE EXTINGUISHER

William A. Beinke, Webster, Iowa

Application November 22, 1946, Serial No. 711,559

7 Claims. (Cl. 169—26)

1

This invention relates to an automatic fire extinguisher adapted to be actuated by an excess of heat in the area in which the extinguisher is disposed, for causing the automatic operation of the extinguisher at a predetermined temperature.

More particularly, it is an object of the invention to provide a fire extinguisher adapted to be released by the breaking of a fusible retaining member for causing a frangible grenade or bulb, containing an extinguishing substance, to be broken by engagement with an anvil portion.

Still another object of the invention is to provide a fire extinguisher capable of being supported in any desired locality and in any position and which is provided with means for distributing the fire extinguishing substance to most effectively accomplish its results.

Various other objects and advantages of the invention will hereinafter become more fully apparent, from the following description of the drawings, illustrating a preferred embodiment thereof, wherein:

Figure 1 is a side elevational view of a preferred embodiment of the invention, shown in a set position;

Figure 2 is a top plan view thereof;

Figure 3 is a vertical, substantially central sectional view, partly in side elevation of the extinguisher;

Figure 4 is a transverse vertical sectional view taken substantially along a plane as indicated by the line 4—4 of Figure 3;

Figure 5 is a horizontal sectional view taken substantially along a plane as indicated by the line 5—5 of Figure 3, and

Figure 6 is an enlarged horizontal sectional view taken substantially along a plane as indicated by the line 6—6 of Figure 1.

Referring more specifically to the drawings, the automatic fire extinguisher in its entirety is designated generally 6 and includes a supporting bracket, designated generally 7 which is substantially L-shaped and which is provided with a leg 8 and a leg 9. The leg 8 is provided adjacent its free end with an opening 10. The bracket 7 is shown supported by a surface 11 by means of a driven fastening 12 which extends through the opening 10 and which is anchored in the number 11. However, the bracket 7 could be secured to a ceiling or overhead surface, or could be supported at the end of a depending hanger, as will hereinafter become apparent.

An elongated strand of relatively resilient wire, designated generally 13, includes an inverted, substantially U-shaped intermediate portion 14 which

is disposed against the outside of the leg 8, adjacent the bight portion of the bracket 7, and longitudinally thereof. The portion 14 is secured to the bracket leg 8 by a clamping plate 15 through which the shank of a nut and bolt fastening 16 extends. Said shank extends between the legs of the portion 14 and through the leg 8 and is adapted to be tightened in a conventional manner for clamping the legs of the portion 14 between the clamping plate 15 and the leg 8 for frictionally securing the strand 13 to the bracket 7. The legs of the strand 13 are provided with integral spring coils 17 disposed beneath and adjacent the clamping plate 15. The complementary ends 18 project outwardly from the remote ends of the coils 17 to form legs which constitute the terminals of the strand 13. The legs 18 are connected in spaced apart relationship, adjacent the coils 17 by a plate 19 which is disposed transversely of the legs 18 and which is provided with struck out tongues or other means 20 which engage partially around the legs 18 for securing corresponding portions thereof in spaced relationship on the plate 19.

A head 21 is formed, preferably of sheet metal, 25 and is provided with an elongated arcuate wall 22 which is concave on its outer side and which is tapered from its outer, toward its inner end. The inner end of the head 21 is open and the outer end thereof is partially closed by an end wall 23 30 which is provided with a relatively large, substantially V-shaped notch 24, as best seen in Figure 2. The arcuate wall 22, adjacent its longitudinal edges, is provided with integral outwardly pressed sleeve portions 25. The wall 22 is provided with a 35 pair of longitudinally aligned sleeve portions 25 adjacent each of its longitudinal edges and said aligned sleeve portions are provided to receive the terminal portions of the legs 18 for mounting the head 21 thereon.

The leg 9 is widened, adjacent its free end to 40 adjacent the bight portion of the bracket 7 and the widened portion thereof is arcuate in cross section and convex on its upper side. An anvil member or plate 26 is secured by rivets or other suitable fastenings 27 to the upper, convex side of the leg, adjacent its free end. The plate or anvil surface 26 is corrugated, as clearly illustrated in Figures 1 and 3. The coils 17 bias the legs 18 downwardly and outwardly relatively 45 to the leg 8 of the bracket 7 and toward the leg 9 thereof and the head 21 is supported by the legs 18 in a position to strike the plate or anvil surface 26 when the legs 18 are moved toward the leg 9.

A frangible grenade or bulb 28 which is adapted

to contain a fire extinguishing substance, not shown, is adapted to be positioned in the concave side of the wall 22 and includes an upper enlarged portion and a restricted lower portion so that the wall of the grenade or bulb is provided with an intermediate annular portion 29 which is tapered downwardly. The bracket leg 8 beneath and adjacent the opening 10 is provided with a struck out upwardly extending tongue or hook 30 adapted to engage a portion 10 of a band 31 which extends around the head 21 and around the intermediate portion of the bulb or grenade 28 and which has a portion engaging the tapered wall portion 29, so that the band 31 not only retains the legs 18 and the head 21 in 15 a retracted, set position adjacent the bracket leg 8, but also supports the bulb or grenade 28 in the head 21 and in substantially the position as illustrated in Figures 1 and 3. The band 31 is formed from a strip of suitable metal, the ends 20 of which may be interlocked in any suitable manner as seen at 32. It will be seen that when the fire extinguisher 6 is in a set position as illustrated in Figures 1, 2 and 3, the fusible band 31 will rupture at a predetermined temperature in 25 response to the pressure exerted thereon through the spring legs 18. When this occurs, the legs 18 will be swung downwardly in a clockwise direction, as seen in Figures 1 and 3, due to the resiliency of the coils 17 and the head 21 will be carried by the legs 18 toward and into engagement with the plate or anvil 26. The bulb or grenade 28 will be carried by the head 21, due to the fact that said head will move more rapidly than the bulb can fall away from the head by gravity. Consequently, the bulb will strike the anvil surface 26 and will be crushed between 30 said surface and the head 21 and the serrations of the surface tend to deflect the fire extinguishing substance laterally and in cooperation with the arcuate wall 22 of the head 21 which will function to deflect the fire extinguishing substance downwardly and toward an area to be protected from fire and which is located beneath the extinguisher 6.

Various modifications and changes are contemplated and may obviously be resorted to, without departing from the spirit and scope of the invention as hereinafter defined by the appended claims.

I claim:

1. In an automatic fire extinguisher, a bracket adapted to be detachably connected to a suitable supporting structure and including an impact receiving surface and a retaining element spaced from said impact receiving surface, an impact member, spring actuated means supported by said bracket and urged in a direction toward the impact receiving surface and on which said impact member is mounted for impelling the impact member into engagement with the impact receiving surface upon actuation of said spring means, a fusible metal band engaging said retaining element and impact member for holding the latter and said spring means in a retracted position until the fusible band is ruptured, and a frangible container of a fire extinguishing substance supported against the impact member by the fusible band and carried with the impact member when the fusible band is ruptured into striking contact with the impact receiving surface for crushing the frangible container.

2. In an automatic fire extinguisher, a bracket adapted to be detachably connected to a suitable supporting structure and including an impact receiving surface and a retaining element spaced from said impact receiving surface, an impact member, spring actuated means supported by said bracket and urged in a direction toward the impact receiving surface and on which said impact member is mounted for impelling the impact member into engagement with the impact receiving surface upon actuation of said spring means, a fusible metal band engaging said retaining element and impact member for holding the latter and said spring means in a retracted position until the fusible band is ruptured, and a frangible container for a fire extinguishing substance carried by said impact member and adapted to be crushed by the engagement of the impact member and impact receiving surface, said container being supported against the impact member by engagement with the fusible band.

3. A fire extinguisher as in claim 2, said fusible band being disposed around said frangible container for retaining it in engagement with the impact member.

4. A fire extinguisher as in claim 1, said impact receiving surface being disposed in substantially a horizontal plane and comprising a corrugated plate adapted to laterally distribute the fire extinguishing substance, when the container thereof is crushed.

5. A fire extinguisher as in claim 2, said impact member being constructed to form a hood over the impact receiving surface, when disposed adjacent thereto, for deflecting the fire extinguishing substance from the crushed container downwardly therefrom.

6. A fire extinguisher as in claim 2, said spring means comprising a strand of resilient wire having an intermediate portion detachably and fixedly secured to the bracket and leg portions having free ends between which free ends of the leg portions said impact member is mounted, 45 said leg portions each being provided with a plurality of resilient convolutions located adjacent said intermediate portion of the wire strand for urging the free ends of said legs toward said impact receiving surface.

7. A fire extinguisher as in claim 2, said impact member being constructed to form a hood over the impact receiving surface when disposed adjacent thereto for deflecting the fire extinguishing substance from the crushed container 55 in a downward direction, and said impact receiving surface being disposed in substantially a horizontal plane and conforming substantially to the curvature of the impact member for cooperation therewith in deflecting the fire extinguishing substance generally in an outward direction around said impact receiving surface.

WILLIAM A. BEINKE.
